(57) **CLAIM**

The ornamental design for a base with domelamps for an automobile entertainment system, as shown and described.

DESCRIPTION

FIG. 1 is a front perspective view of a base with domelamps for an automobile entertainment system showing my new design.

FIG. 2 is a rear perspective view of thereof.

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a bottom plan view thereof.

The broken lines in the drawings are for the purpose of showing environmental structure and do not form part of the claimed design.
